HOLDER FOR CARDS PRESCRIBING A HOSPITAL PATIENT'S TREATMENT

Harvey N. Bowen, Northfield, Ill., assignor to Hollister Incorporated, Chicago, Ill., a corporation of Illinois

Filed Sept. 16, 1959, Ser. No. 57,575

Term of patent 14 years

(Cl. D1—3)

Fig. 2.

Fig. 1.

Fig. 3.

Fig. 4.

Fig. 1 is a front elevation of a holder for cards prescribing a hospital patient's treatment showing my new design;

Fig. 2 is a plan thereof;

Fig. 3 is a side elevation thereof; and

Fig. 4 is a bottom view thereof.

The dominant features of my design are shown in solid lines. The rear face of the holder is substantially plain.

I claim:

The ornamental design for a holder for cards prescribing a hospital patient's treatment, as shown and described.
